BY HIS ATTORNEY Harry Smith

UNITED STATES PATENT OFFICE.

FRANK APPLETON, OF PHILADELPHIA, PENNSYLVANIA, ASSIGNOR, BY MESNE ASSIGNMENTS, TO SCOTT & WILLIAMS, INCORPORATED, A CORPORATION OF MASSACHUSETTS.

DEFECTIVE-YARN DETECTOR FOR KNITTING-MACHINES.

1,251,459.

Specification of Letters Patent.

Patented Jan. 1, 1918.

Application filed March 10, 1916. Serial No. 83,251.

To all whom it may concern:

Be it known that I, FRANK APPLETON, a citizen of the United States, residing at Philadelphia, Pennsylvania, have invented 5 certain Improvements in Defective-Yarn Detectors for Knitting-Machines, of which the following is a specification.

The object of my invention is to provide a knitting machine with means whereby, 10 when the free forward passage of the yarn to the needles is arrested and said yarn is therefore subjected to tension, it will not break at or near the needles and thus cause the latter to cast off the web, but will be 15 severed at a point remote from the needles in order that the yarn supplied to the latter will not be exhausted before the machine can be stopped.

Another feature of my invention consists 20 in so connecting the yarn severing and stop-motion devices that these operations will be performed simultaneously.

In the accompanying drawings—

Figure 1 is a view illustrating the relation 25 to each other of the needles, yarn guides and yarn severing devices of the machine;

Fig. 2 is a top view, on an enlarged scale, 30 of said yarn severing devices and of some of the yarn guides;

Fig. 3 is a front view of the same looking 35 in the direction of the arrow *a* Fig. 2;

Fig. 4 is a rear view of part of the same looking in the direction of the arrow *b*, Fig. 2;

Fig. 5 is an end view looking in the direction 40 of the arrow *c*, Fig. 2, and

Fig. 6 is a view similar to Fig. 5, but omitting certain yarn guides there shown and illustrating one of the parts in a different position.

When, in an ordinary knitting machine, the free forward feed of the knitting yarn is interfered with for any reason such, for instance, as a defect in the yarn or in the 45 guides therefor, the yarn is subjected to tension and is soon broken. Such breaks usually occur at a point close to the needles, thereby at once cutting off the further supply of yarn to said needles and causing the 50 latter to cast off the knitted web which is being produced.

My invention consists in providing, at a point relatively remote from the needles, a 55 yarn severing device which is inoperative

so long as the yarn is being fed freely to the needles, but, when the yarn is subjected to tension, is caused to sever the yarn at such remote point, so that the supply of yarn to the needles will continue until the machine can be stopped. In order to insure 60 this result, the stop motion device is actuated at the same time as the yarn severing device.

In the accompanying drawings, 1 represents the needles of the knitting machine 65 and 2 a latch guard carrying the guide whereby the knitting yarn is fed to said needles. Rising from the fixed frame of the machine is a post 3 having at an elevated point a projecting arm 4 which carries the devices constituting the subject of my invention.

Upon a head at the outer end of the arm 4 is fixedly mounted an arm 5 having depending guide loops 6 for the yarn, and 75 pivotally mounted in said outer end of the arm 4 is a trigger 7 having upwardly projecting yarn guiding loops 8 alternating with the loops 6, as shown in Figs. 1, 2 and 3.

The trigger 7 is carried by a head 9 (Fig. 4) upon one end of a rock shaft 10 which is mounted so as to be free to swing in a bearing in the arm 4, and has at its opposite end a cam formation consisting, in the 85 present instance, of a flattened rib 11 projecting outwardly from and extending diametrically across the end face of the shaft, as shown in Figs. 2 and 3. Slidably mounted in bearings on the arm 4 is a locking bolt 90 12 having a downwardly bent inner end 13, and between the latter and a hook 14 on the arm 4 is interposed a coiled spring 15, which tends to press said inner end of the bolt 12 constantly against the cam formation 95 11 on the end face of the rock shaft 10. Rigidly mounted on the end of the arm 4 is a shear blade 16, and pivotally mounted in contact with said blade 16 is a swinging shear blade 17, which, in the present instance, constitutes one arm of a lever 18 whose other arm 19 constitutes a trip arm for actuating the stop motion device of the machine, said trip arm being connected to said stop motion device by any suitable form 100 105 of attachment 20.

Any suitable form of stop motion device may be employed the particular character of

the same being immaterial to my present invention. For convenience, however, I have shown, in Fig. 1, a stop motion device such as constitutes the subject of a separate application for patent filed by me, Serial No. 83,252, of March 10, 1916, but for a proper understanding of my present invention no detailed description of such stop motion device will be necessary:

10 When the parts are in the position shown in Figs. 2, 3, 4 and 5 of the drawing the shear blades are separated so that the knitting yarn can pass freely between them, being properly directed in its course by means 15 of guide loops 21 and 22 located respectively in front and rear of the shear blades, as shown. At such time the trip arm 19 of the lever 18 is depressed, as shown in Fig. 5, and is locked in this position by engagement 20 of said trip arm with the forward end of the bolt 12, against the normal tendency of the arm 19 to rise under the action of a coiled spring 23 interposed between the outer end of said arm 19 and the end of a 25 fixed arm 24 rigidly mounted upon and projecting upwardly from the arm 4, as shown in Figs. 2, 3 and 5.

The yarn passes from the guide loop 25 at the end of the trigger 7 over an elevated 30 guide loop 26, hence if, at any time, the free forward passage of the knitting yarn is obstructed and said yarn is subjected to tension, the trigger 7 will be caused to rise from the position shown by full lines in 35 Figs. 1 and 3 to that shown by dotted lines α in said figures, and this will have the effect of turning the rock shaft 10 so as to carry the edge of the cam rib 11 away from the inner end of the bolt 12 and thereby permit 40 retraction of the latter under the influence of the spring 15 until it bears against the flat face of the rib. This movement withdraws the end of the bolt 12 from locking engagement with the trip arm 19 of the lever 45 18 and thereby permits said arm to rise under the action of the spring 23 so as to close the shear blade 17 against the blade 16 and thus sever the yarn and at the same time cause the trip arm 19, through the medium 50 of the connection 20, to operate the stop motion device of the machine and thereby arrest the knitting operation before the length

of yarn intervening between the shear blades and the needles has been exhausted, the casting off of the web from the needles 55 because of failure of the yarn supply being thus prevented.

The machine can be readily restored to operative condition again by joining the ends of the knitting yarn and resetting the 60 stop-motion device after first correcting the defect which originally caused the free forward feed of the yarn to be interfered with.

The stoppage of the machine will also be effected in the event of the breaking of the 65 yarn between the bobbin and the needles, the trigger 7 in such case falling to the position shown by dotted lines γ in Fig. 3 and causing an operation of the parts similar to that which was effected by the elevation of 70 said trigger to the position shown by dotted lines c in Fig. 3.

I claim:

1. The combination of the needles of a knitting machine, yarn guides including a 75 trigger engaging the yarn at a point relatively remote from the needles, a rock shaft carrying said trigger and having a duplex cam formation thereon, a stop motion operating lever, and a bolt for locking said lever 80 in inoperative position, said bolt being under control of said cam formation whereby the stop mechanism will be operated by movement of the trigger in either direction.

2. The combination of the needles of a 85 knitting machine, yarn guides including a trigger engaging the yarn at a point relatively remote from the needles, a rock shaft carrying said trigger, and having on one end face of the same a flat sided rib projecting 90 from said face and extending diametrically across the same, a locking bolt normally pressing against an end of said rib, and means for moving said locking bolt so as to cause it to press against a flat side of the 95 rib when the latter is turned from its normal position.

In testimony whereof I have signed my name to this specification in the presence of two subscribing witnesses.

FRANK APPLETON.
